(57) **CLAIM**

The ornamental design for a ring-shaped vehicle accessory, as shown and described.

DESCRIPTION

FIG. 1 is a perspective view of the ring-shaped vehicle accessory of the invention.

FIG. 2 is a right side view of the ring-shaped vehicle accessory of FIG. 1, the left side view being a mirror image thereof.

FIG. 3 is a front view of the ring-shaped vehicle accessory of FIG. 1.

FIG. 4 is a back view of the ring-shaped vehicle accessory of FIG. 1.

FIG. 5 is a top view of the ring-shaped vehicle accessory of FIG. 1.

FIG. 6 is a bottom view of the ring-shaped vehicle accessory of FIG. 1.

FIG. 7 is a perspective view of the ring-shaped vehicle accessory according to a second embodiment of the invention.

FIG. 8 is a right side view of the ring-shaped vehicle accessory of FIG. 7, the left side view being a mirror image thereof.

FIG. 9 is a front view of the ring-shaped vehicle accessory of FIG. 7.

FIG. 10 is a back view of the ring-shaped vehicle accessory of FIG. 7.

FIG. 11 is a top view of the ring-shaped vehicle accessory of FIG. 7; and,

FIG. 12 is a bottom view of the ring-shaped vehicle accessory of FIG. 7.

The broken lines shown in FIGS. 1-12 are for illustrative purposes only and form no part of the claimed design.
